UNITED STATES PATENT OFFICE.

JACOB MOSKOVITZ, OF GLASSPORT, PENNSYLVANIA.

DISPLAY DEVICE.

Application filed November 4, 1924. Serial No. 747,729.

This invention relates to display devices and more in particular to anti-theft display devices used in stores to prevent so called shop-lifting.

5 One of the principal objects of this invention is to provide a display device of artistic appearance having a series of locking means for the goods to be displayed, said means being adapted to be easily 10 opened simultaneously from a central point. Another object is to provide a device which can be easily modified to serve for the display of various kinds of goods, such as neckties, ribbons, hosiery and so forth. A 15 further object is to produce a device in which the individual locking means are adapted to adjust themselves automatically to the varying thickness of the goods held by them. Additional features and advantages of this invention may appear 20 from the following description considered in connection with the accompanying drawings, in which:

Fig. 1 is a front elevation, partly in 25 section, showing the preferred embodiment of my display device.

Fig. 2 is a top plan view of Fig. 1.

Fig. 3 is a section taken on line 3—3, in Fig. 1.

30 Fig. 4 is a fractional view, partly in section, showing the central operating mechanism of the device.

Fig. 5 is a cross-section of the operating mechanism taken at right angles to the 35 view shown in Fig. 4.

Fig. 6 is an enlarged side view showing a lock in closed position.

Fig. 7 is a similar view showing the lock in open position.

40 Fig. 8 is a top plan view of Fig. 7.

Fig. 9 is a rear elevation of Fig. 7.

Fig. 10 is a fractional view showing a detail of construction of the locking lever.

Fig. 11 is a cross-section taken on line 45 11, Fig. 10.

Referring to the drawings, it will be noted that my device consists of a series of locking means 1 disposed concentrically about the central post 2 of a stand 3 and mounted upon a preferably polygonal base 4 secured at the upper end of said stand.

All the locking means are built alike and each comprises a pair of guide-bars 5 securely held on the base 4 by means of nuts 6, engaging the suitably threaded inner ends of said guide-bars. The latter

are connected at their outer ends by means of the front plate 7, held by the ornamental nuts 52, in order to add to their rigidity and maintain their parallel alignment.

Guided by said guide-bars is a clamping plate 8 to which is centrally secured a substantially horizontal push-rod 9 having at its inner end an upwardly bent portion 10 provided with an aperture 11 which is engaged by the inner end 12 of a coiled tension spring 13. The front end 14 of the latter is hooked in a hole 15 cut in a lug 16 preferably formed integral with the base 4 by the process of stamping and bending. The push-rod is additionally guided for horizontal reciprocating movement by a snug fitting aperture cut in said base.

Suitably located upon the push-rod and 75 permanently secured thereto by rivets 17 is a downwardly directed stirrup 18 having in each of its two legs a guide-slot 19 of adequate length and open at the bottom.

These slots are engaged by a pin 20 driven 80 tightly in the elbow portion of the operating L-shaped lever 21, the shorter arm 22 of which is rockably mounted upon a pin 23 secured in two depending and parallel lugs 24 stamped out of the base 4 and adjacent the lower edge thereof. The longer arm 25 of said operating lever is substantially horizontal when the clamping plate 8 is in its closed position, as shown in Fig. 6, and terminates in an upward curve having 90 a rounded tip 26.

In order to prevent the accidental falling out of the pin 20, the latter is preferably provided with an enlarged portion or flange 27 of greater diameter than the 95 width of the slots 19 and of the same thickness as the operating lever. By using this construction, it will be seen that even though this pin should become loose in the operating lever, it will always be kept in 100 its proper place by the legs of the stirrup.

The central operating mechanism for 105 operating simultaneously all the operating levers is mounted upon the central post 2. The latter is preferably made of tubing in which a longitudinal slot 28 of suitable length and location has been cut. Slidably mounted upon the central post is a sleeve member 29 the upper end of which is outwardly threaded to receive two lock nuts 30 and 31 between which is securely held the substantially semi-circular plate 32 which is 110

bent downwardly along the curved edge to increase its stiffness and also to facilitate the initial gliding movement of the tips 26 along its under-side.

- 5 The lower end of said sleeve is inserted in a thimble 33, preferably knurled outwardly to secure a better grip for the hand and held for rocking movement upon the sleeve by means of a set-screw 34 having a reduced 10 extension 35 passing through an oblong aperture 36 cut in the sleeve and engaging the longitudinal slot 28. The latter is provided at the top and bottom with the lateral recesses or notches 37 and 38 which are engaged 15 by the set-screw for the purpose of holding the operating mechanism in either one of its extreme positions. The aperture 36 is made oblong to allow the rocking of the thimble independently of the sleeve 29 and connected parts.

The lower ends of the four legs of the stand 3 and the central post 2 are secured in a spider comprising four spokes 39 riveted at the center to the plate 40, to which the 25 central post is secured by means of the nuts 41 and 42. The outer extremities of these spokes are drilled to receive the legs of the stand and have downwardly bent portions 43 through which are passed the bolts 44 to securely hold said legs in place. A cross bar 45 is also used to connect the two extreme legs of the stand and the central post to give the device additional rigidity.

The device is also stiffened at the top by 35 means of suitably curved radial stays 46 having one of their ends secured to the inside of the base 4 in any desired manner, while the other ends are riveted to the top plate 47 secured to the center post by means 40 of the nut 48 and the knob 51. The open spaces between the various stays are preferably covered up by means of suitably shaped shields 49 to improve the general appearance of the device and hide the 45 several parts of the operating mechanism of the locking means and thus protect them against tampering by evil minded persons. These shields are held in place by means of small lugs 50 provided in the stays.

50 The central post is provided at the top with a knob 51 which is held by the operator to stabilize the device while he operates the central operating mechanism and which also serves to improve the appearance of the device.

The method of operating my display device is substantially as follows.

Assuming that the locks 1 be in their 60 closed position and that an operator wishes to open them to either remove or introduce some goods, he first grips with one hand the operating thimble 33, gives it a slight twist to the left to disengage the set-screw 34 from the notch 37 and then pulls the whole 65 central operating mechanism down as far

as the slot 28 will permit. He then gives the thimble a slight turn to the right to cause the set-screw to engage the notch 38, thereby locking the operating mechanism in its lowermost position. As will be readily 70 understood, the downward movement of the operating mechanism causes the various operating levers 21 to open their corresponding locking means thus allowing the operator to insert or remove the goods. To close the 75 locks, the thimble is turned to the left and the central operating mechanism is then forced up into the closed position by the heretofore stressed springs 13.

80 While I have illustrated and described herein the preferred embodiment of my invention, and one which I have found in actual use to be very practical, it may be thought necessary or desirable after continued use to make slight changes in the 85 construction and arrangement of the details of my invention, and I intend to include in this application all such variations as fall within the scope of the appended claims.

I claim:

1. In a display device of the character described, a plurality of concentrically disposed locking means, a unitary base therefor; each of said locking means comprising a pair of parallel guide bars, a front plate 95 permanently connecting same and a clamping plate reciprocably movable between said guide bars and having a centrally disposed push rod; a spring member connected to said push rod and normally holding said clamping plate against said front plate; a stirrup depending from said push rod and having longitudinal slots provided therein; a substantially L-shaped lever; a fulcrum therefor positioned on said base; a pin secured in said lever and engaging said slots, and centrally disposed unitary means for simultaneously opening said locking means.

2. In a display device of the character described, a plurality of concentrically disposed locking means; a base therefor; each of said locking means comprising a pair of parallel guide bars; a front plate permanently connecting same and a clamping plate reciprocably movable between said guide bars and having a centrally disposed horizontal push rod; a spring member connected to said push rod and normally holding said clamping plate against said front plate; a stirrup depending from said push rod and having longitudinal slots provided therein; a substantially L-shaped lever, a fulcrum therefor positioned on said base; a pin secured in said lever and engaging said slots; means provided on said pin to prevent the accidental falling out thereof from said lever, and centrally disposed unitary means for simultaneously opening said locking means.

3. In a display device of the character de-

scribed, a plurality of concentrically disposed locking means; a base therefor; a stand for said base comprising a plurality of legs and a central post; each of said locking means comprising a pair of parallel guide bars; a front plate permanently connecting same and a clamping plate reciprocably movable between said guide bars and having a centrally disposed horizontal push rod; a spring member connected to said push rod and normally holding said clamping plate against said front plate; a stirrup depending from said push rod and having longitudinal slots provided therein; a substantially L-shaped lever having a short vertical arm 15 and a long horizontal arm terminating with an upward bend; a fulcrum for said lower arm positioned on said base; a pin secured in said lever and engaging said slots, and an operating plate longitudinally movable along 20 said central post and adapted to act upon the upward bend of each of said L-shaped levers to simultaneously open said locking means.

In testimony whereof I affix my signature.

JACOB MOSKOVITZ.
